UNITED STATES PATENT OFFICE.

JAMES H. BAKER, OF PITTSBURG, PENNSYLVANIA.

BRAKE-HANGER FOR CAR-TRUCKS.

No. 919,676.

Specification of Letters Patent.

Patented April 27, 1909.

Application filed September 8, 1908. Serial No. 451,976

To all whom it may concern:

Be it known that I, JAMES H. BAKER, of Pittsburgh, Allegheny county, Pennsylvania, have invented a new and useful Brake-
5 Hanger for Car-Trucks, of which the following is a full, clear, and exact description, reference being had to the accompanying drawings, forming part of this specification, in which—

10 Figure 1 is a partial side elevation of a truck frame showing my brake hanger in position; Fig. 2 is a cross sectional view; and Fig. 3 is a modification.

15 My invention has relation to brake hangers for car trucks, and more particularly to that class of car trucks in which the brake hangers are secured to the side frames and the latter are composed either in whole or in part of steel castings. In casting these side frames, 20 it is a matter of difficulty to cast the brake hangers integral with the side frames, for the reason that these hangers must have sufficient projection inwardly from the side frames to bring them in line with the car 25 wheels. This makes it necessary for them to have a considerable overhang, and when it is attempted to cast them integral with the side frames, they are apt to break in service. 30 The part of the casting where the hangers join the side frames being a weak point, and likely to be further weakened by strains set up in the casting due to unequal shrinkage. Further, these frames bend by shrinkage in 35 cooling, and any projection on the sides makes it much more difficult to straighten them. The proportionately larger amount of metal on one side when the brake hanger is cast integral with the frame causes them to bend still more than otherwise.

40 The object of my invention is to provide a simple and strong hanger which can be readily attached to the bolster guides or columns of the side frame, and which is secured thereto in such manner as to enable it to resist the 45 strains to which it is subjected.

Referring to the drawings, the numeral 2 designates the side frame of a car truck having the bolster guides or columns 3.

4 designates my improved hanger consisting of a bracket, preferably an integral casting of steel or malleable iron, and having an inwardly projecting arm 5, formed at its lower end with the eyes 6 to which the usual brake hanger strap or rod 7 is connected. 55 The hanger also has the base portion 8 adapted to fit against the column 3, with a

projection 9 thereon extending inwardly into the interior of the column through a slot 10. The portion 8 has an upward extension 11, which is bolted or riveted to the top member 60 12 of the compression member or top arch bar of the side frame and is also provided with a bolt or rivet hole 13, at its lower portion by means of which the bracket is further secured to the column. An additional support is given to the bracket or hanger at its base by having the part 9 rest on the bottom of the opening in the column just below the rivet 13, Fig. 3. The angle of the bracket between the arm 5 and the base portion 8 is 65 preferably reinforced by one or more ribs 14, two of such ribs being shown in the present instance.

In the modification shown in Fig. 3, instead of securing the upper portion of the 70 bracket to the compression member 12 by means of a bolt or rivet, it is provided at its upper end with the hooked flange 16, which fits over the flange 17 of said compression member and is secured to the web portion 18 thereof with one or more bolts or rivets 19. The rivets are in all cases preferred for fastening the bracket, owing to the liability of bolts to become loosened in service.

It will be seen that owing to the long reach 85 from the point where the brake hanger strap 7 is connected to the bracket, to the point where the upper end of the base portion of the bracket is connected to the side frame, a very secure fastening is provided and the 90 bracket is enabled to stand the strains to which it is subjected without shearing or breaking the fastenings. The projection 9 extending into the column also stiffens the bracket and greatly relieves the fastenings 95 from strains. The projection 9 is placed as far back of the line of the hanger 7 as the leaving of bolster guide room will permit, in order to support the eye of the carrier from going in toward the side of the frame when 100 pulled by the hanger 7.

The brackets can be readily cast separately from the side frames and can be quickly and readily secured thereto.

It will be understood that the particular 105 form of the bracket can be changed from that shown, without departing from my invention.

What I claim is:

1. A brake hanger for car trucks, comprising a bracket having an inwardly projecting arm, and a base portion, said arm having

means at a point whereby below the under side of the adjacent portion of the top arch bar of the side frame for the attachment of a brake hanger strap, and means for securing 5 the base portion of the bracket to the side frame both above and below the center of the arm; substantially as described.

2. A brake hanger for car trucks, consisting of a bracket adapted to be secured to the 10 side frame of the truck, and means whereby said bracket may be rigidly secured to the upper portion of a side frame and also to the bolster guide or column thereof at a point distant from the point where it is secured to 15 the upper portion of the side frame, substantially as described.

3. The combination with a side frame of a car truck, of a brake hanger bracket secured thereto, said bracket being secured to the 20 upper portion of the compression member of the side frame and also to a bolster guide or column of such frame at a point distant from its other point of connection to the side frame, substantially as described.

25 4. A brake hanger for car trucks, consisting of an integral bracket having an arm projecting inwardly at substantially right angles to the longitudinal plane of the side frame of the truck, and a base portion at 30 right angles to said arm, and provided with means for its attachment to the side frame of the truck, substantially as described.

5. A brake hanger for car trucks, comprising a bracket having an inwardly projecting 35 arm and a base portion at an angle to the arm, said base portion having means whereby it may be secured to the side frame of a truck, and also having a projection arranged to extend into and engage the bolster guide or 40 column of the side frame, substantially as described.

6. A brake hanger for car trucks, consisting of an integral bracket having an arm projecting inwardly at substantially right 45 angles to the longitudinal plane of the side frame of the truck, and a base portion, and one or more strengthening ribs connecting said portions, substantially as described.

7. In a car truck, the combination with a side frame having its column provided with an opening therein, of a brake hanger bracket provided with a projection extending through said opening into the column, and the hanger being also secured to the side frame of the truck at a point above and distant from the 55 said projection, substantially as described.

8. In a car truck, the combination with a side frame having its column provided with an opening therein, of a brake hanger bracket provided with a projection extending through 60 said opening into the column, said projection bearing against the lower edge of said opening, substantially as described.

9. In a car truck, the combination with a side frame having its column provided with an opening therein, of a brake hanger bracket provided with a projection extending through 65 said opening into the column, said bracket having means for the connection therewith of a brake hanger, and the said projection 70 being back of the line of said hanger, substantially as described.

10. A brake-hanger for car trucks having an arm to which the brake hanger straps may be connected, and also having a base portion adapted to be secured to the bolster column and formed with an upward extension adapted to engage and be secured to the top of the compression member of a truck 75 side frame, substantially as described.

11. In a car truck, the combination with a side frame having its column provided with an opening, and having a flanged compression member, of a brake hanger bracket formed with a projection arranged to engage 85 the opening in said column, and also having an upward extension arranged to engage the flanged top of said compression member; substantially as described.

In testimony whereof, I have hereunto set 90 my hand.

JAMES H. BAKER.
